DESIGN FOR A CARRIAGE FOR BATTERY CHARGER

Henry E. Hunt, Los Angeles, Calif.

Application January 15, 1941, Serial No. 98,061

Term of patent 7 years

To all whom it may concern:

Be it known that I, Henry E. Hunt, a citizen of the United States and a resident of the city of Los Angeles, in the county of Los Angeles and State of California, have invented a new, original, and ornamental Design for a Carriage for Battery Charger, of which the following is a specification, reference being had to the accompanying drawing, forming part thereof.

In the drawing:

Figure 1 is a perspective view of a carriage for battery charger showing my new design.

Figure 2 is a top plan view thereof.

Figure 3 is a side elevational view with a portion of the wheel broken away to show the chassis portion.

I claim:

The ornamental design for a carriage for battery charger, substantially as shown.

HENRY E. HUNT.
